UNITED STATES PATENT OFFICE.

CHARLES M. BLYDENBURGH, OF RIVERHEAD, NEW YORK.

VEHICLE-SPRING.

SPECIFICATION forming part of Letters Patent No. 380,169, dated March 27, 1888.

Application filed December 2, 1887. Serial No. 256,749. (No model.)

To all whom it may concern:

Be it known that I, CHARLES M. BLYDENBURGH, a citizen of the United States, residing at Riverhead, (Long Island,) in the county 5 of Suffolk and State of New York, have invented certain new and useful Improvements in Vehicle-Springs, of which the following is a full and clear description, reference being had to the accompanying drawings, forming 10 part of this specification, in which—

Figure 1 represents a side elevation of one of my improved springs. Fig. 2 is a bottom plan view of the same. Fig. 3 is an enlarged detail of the central portion of the springs, 15 showing the manner of crossing the springs.

My invention relates to springs supported upon the front and rear axles of a vehicle; and it consists in the improved spring hereinafter fully described and specifically claimed.

20 To enable others skilled in the art to which my invention appertains to make and use the same, I will now describe its construction and indicate the manner in which the same is carried out.

25 In the said drawings, A A represent semi-elliptical or curved springs secured at opposite ends by shackles *a* to the bars B. These bars sustain the springs and cross the axle, said bars being secured to the axle by any appropriate means, and they may be made of wood or iron, or when extra softness is wanted I sometimes employ ordinary leaf-springs in 30 place of the bars.

From their points of connection with the 35 bars the springs A A extend diagonally from one bar to another, crossing each other at the center, as shown in Fig. 2, and each spring comprises two plates or leaves, *b* *b'*, having straight or flat central portions, *c* *c'*, said flat 40 portion on the upper leaf, *b*, of each spring being not so long as the corresponding portion of the other leaf, *b'*, whereby a space is left between the contiguous faces of the plates or leaves *b* *b'* for the introduction of suitable pil-

45 lars, *d*, which are placed upon each side of the central pivot-bolt. This construction also permits the central portions of the leaves of one spring A to pass between the corresponding portions of the leaves of the other spring without necessitating the cutting away of any part 50 of either spring, thus retaining their full strength.

To the top of the central portions of the springs are secured the cross-bars C, which support the usual fifth-wheel, the lower disk, 55 *e*, of which is shown in Fig. 1, and through the central portions of the crossed springs A A and bars C the usual pivot-bolt, *D*, is passed and secured.

The peculiarities and advantages of my invention consist in the crossing of the springs A A in the center without cutting the plates or having them fit imperfectly. This is readily accomplished by making the central portions of the springs about straight, the straight 65 part of each successive leaf or plate being somewhat shorter than the one over which it fits, thereby making it possible to fit the leaves of each spring closely together except at the center or flat portion.

70 I am enabled by the above construction to dispense with the reach when a platform spring-wagon is to be made.

If a light vehicle is to be constructed, I draw the ends of the crossed springs closer together and pivot or couple them to a short bar, and then put in the ordinary reach king-pin, &c., to keep the axles from drawing out of place and the springs from canting forward.

75 The construction before stated will not rock 80 or roll forward and backward when used on rough roads, as do those gears which have but one spring placed lengthwise of the axle. The same is also true when two parallel springs are placed close to either side of the axle.

85 When my invention is applied to a platform-gear and the ordinary reach dispensed with, I can use an ordinary short five-foot or five-foot-six-inch body, whereas in the ordinary platform-gears this cannot be done unless long 90 bars ("body-loops") project out back of the body for the back cross-spring to rest against.

These are only a few of the advantages to be gained by the use of my invention, which is applicable to any style of wagon-gear having 95 either straight, curved, or cranked axles.

Single-plate (such as ribbed steel) springs may be used instead of plural plates when lightness of weight is important.

Having thus described my invention, what I 100 claim as new, and desire to secure by Letters Patent, is—

1. The curved springs A A, secured to the bars B and extending along the axle diag-

onally from one bar to another, said springs comprising a plural number of leaves or plates having flat central portions of unequal lengths, forming a space between said leaves, whereby the leaves or plates of each spring pass between and cross the leaves or plates of the contiguous spring, substantially as described.

2. The springs having lower leaves or plates, b' , with flat central portions, and the upper leaves or plates, b , fitted to the lower leaves, having flat central portions shorter

than the flat portions of the lower leaves, whereby a space is left between the central portion of each contiguous leaf, in combination with the bars B, to which the ends of the 15 springs are secured, and the pillar plates or washers in said spaces upon each side of the central pivot-bolt, substantially as described.

CHARLES M. BLYDENBURGH.
